UNITED STATES PATENT OFFICE.

WILLIAM F. GIBBS, OF AUBURN, NEW YORK.

CAR-BRAKE.

SPECIFICATION forming part of Letters Patent No. 478,003, dated June 28, 1892.

Application filed March 10, 1892. Serial No. 424,418. (No model.)

To all whom it may concern:

Be it known that I, WILLIAM F. GIBBS, of Auburn, in the county of Cayuga and State of New York, have invented a new and Improved 55 Car-Brake, of which the following is a full, clear, and exact description.

My invention relates to improvements in car-brakes, and especially to street-car brakes. In electric street-cars there is but little unoccupied space beneath the cars, and it is desirable to have a brake mechanism which will have the necessary power and which will occupy but little space.

The object of my invention is to produce a 15 simple form of brake mechanism which will meet this requirement and which may also be adjusted so that the brake-shoes shall be simultaneously and with equal force applied to both the front and rear wheels of a car. 20 To this end my invention consists in certain parts and details and combinations of the same, as will be hereinafter described and claimed.

Reference is to be had to the accompanying 25 drawings, forming a part of this specification, in which similar figures of reference indicate corresponding parts in all the views.

Figure 1 is a broken vertical section on the line 1 1 in Fig. 2, showing the application of 30 the brakes and brake mechanism to a car and to the car-wheels. Fig. 2 is a vertical section on the line 2 2 in Fig. 1, and Fig. 3 is a detail sectional view of the crank-arm and its connections for operating the brakes.

35 In the drawings, 10 represents the bottom of the car, 11 its wheels, and 12 the brake-shoes, which are of the usual kind and which are suspended from the car-bottom by means of rods 13 or from the trucks in the usual way, 40 the shoes being held so as to be pressed against the faces of the wheels.

A squared rod 14 extends transversely beneath the car and about midway between the front and rear wheels 11, the rod having cylindrical ends which are journaled in supports 45 15, attached to the car-bottom, although the rod may be supported in any convenient way. The rod is provided with a central crank-arm 16, which is normally held by a spring 16^a, so 50 as to throw the brakes out of engagement with the wheels, and this crank-arm has a segmental

free end 17, which is recessed, as shown at 18, and which is adapted to be secured to a chain 19, which chain connects with a crank or its equivalent for operating the brakes in the usual manner. Fixed to the rod 14 near the ends are disks 20, and each disk is pivotally connected with a pair of arms 21, these arms being secured to the disk on opposite sides of the rod 14 and made to extend in opposite directions. The outer ends of the arms 21 are pivoted to the upper ends of similar and oppositely-arranged levers 22, which are arranged in a nearly-vertical position beneath the car and are fulcrumed on journaled pins 65 23, the levers being thickened opposite the pins to give them the necessary strength, and the pins of the two levers are connected by straps 24, so that the levers may have a rigid fulcrum and be able to move in unison. 70

The journal-pins 23 are held to move in curved slots 25, which are produced in the side pieces 26 of a fender 27, this fender and side pieces being similar to that on the most common form of electric cars; but where a 75 similar support is not found on the cars the pins may be held to move in any suitable bearing, or the brake will work successfully even though the pins are not supported by bearings. The lower ends of the levers 22 are 80 pivotally connected with rods 28, each lever being connected to a rod independently and the rods being made to extend backward and forward, so as to connect with the brake-shoes of the front and rear wheels. The rod 28 of 85 the forward lever extends backward and the rod of the rear lever forward, as shown in Fig. 1.

The rods 28 are each connected to a turn-buckle or nut 29, and these connect with hooks 30, which are secured to the backs of the brake-shoe 12. The arrangement of levers above described is produced on each side of the car, as shown in Fig. 2, and it will be seen that the entire mechanism will occupy but little space. It is only necessary to move the crank-arm 16 by means of the chains 19 to apply the brake, as this movement will turn the rod 14 and the disks 20, which movement of the disks will move the arms 21 in the opposite directions, thus pushing the upper ends of the levers 22 apart, and when these upper ends are pushed apart the lower ends will be moved 100

toward each other, thus actuating the rods 28 and forcing the brake-shoes firmly upon the wheels 11.

It will be seen that if the brake-shoes are irregular the lost motion thus produced may be compensated for by simply turning one of the nuts 29, and the mechanism may thus be quickly and easily adjusted, so that the shoes will always bear evenly upon both the front 10 and rear wheels.

Having thus fully described my invention, I claim as new and desire to secure by Letters Patent—

1. The combination, with the brake-shoes suspended from the car and adapted to engage the wheels, of levers arranged between the front and rear wheels and having connected fulcrums, adjustable rods connecting the lower ends of the levers with the brake-shoes, 15 a crank-shaft journaled beneath the car-bottom and provided with disks, and oppositely-extending arms secured to opposite sides of the disks and also to the free ends of the levers, substantially as described.
2. A car-brake comprising brake-shoes suspended from the car-bottom adjacent to the wheels, levers arranged in pairs on opposite sides of the car and between the front and rear wheels, said levers having movable and 25

connected fulcrums, rods connecting the lower ends of the levers with the brake-shoes, and a crank mechanism for operating the levers, substantially as described.

3. A car-brake comprising brake-shoes suspended adjacent to the wheels, levers arranged 35 in pairs on opposite sides of the car between the front and rear wheels, pins forming the fulcrums of the levers and held to slide in bearings, straps connecting the pins of each pair of levers, adjustable rods connecting the lower ends of the levers with the brake-shoes, and a crank mechanism for operating the levers, substantially as described.

4. A car-brake comprising brake-shoes suspended from the car so as to engage the wheels, 45 levers arranged in pairs on opposite sides of the car and between the wheels, said levers having movable and connected fulcrums, adjustable rods connecting the lower ends of the levers with the brake-shoes, a crank-shaft 50 journaled beneath the car and having disks at each end, and oppositely-extending arms secured to each disk and to the free ends of the levers, substantially as described.
